(57) **CLAIM**

The ornamental design for a digital camera, as shown and described.

DESCRIPTION

FIG. 1 is a perspective view of a digital camera showing our new design;

FIG. 2 is a front view thereof;

FIG. 3 is a top plan view thereof;

FIG. 4 is a bottom plan view thereof;

FIG. 5 is a right side elevational view thereof;

FIG. 6 is an enlarged view of the portion defined by crop lines 6-6 in FIG. 5; and,

FIG. 7 is a cross-sectional view of a part taken along line 7-7 in FIG. 6 with the internal structure omitted.

The features shown in broken lines in the drawings depict environmental subject matter only and form no part of the claimed design.

The dot-dashed lines denote the boundary of the claim and form no part of the claimed design.
